Atty.

UNITED STATES PATENT OFFICE.

HANS WIEDERKEHR, OF ZURICH, SWITZERLAND, ASSIGNOR TO THE FIRM OF SCHWEIZERISCHE LOKOMOTIV & MASCHINENFABRIK, OF WINTERTHUR, SWITZERLAND.

REVERSING-GEAR FOR INTERNAL-COMBUSTION ENGINES.

1,394,243.

Specification of Letters Patent.

Patented Oct. 18, 1921.

Application filed November 3, 1920. Serial No. 421,575.

To all whom it may concern:

Be it known that I, HANS WIEDERKEHR, a citizen of the Republic of Switzerland, residing at Zurich, Switzerland, have invented 5 certain new and useful Improvements in Reversing-Gears for Internal-Combustion Engines; and I do hereby declare the following to be a clear, full, and exact description of the invention, such as will enable others 10 skilled in the art to which it appertains to make and use the same, reference being had to the accompanying drawing, and to letters or figures of reference marked thereon, which form a part of this specification.

15 This invention relates to improvements in reversing gears for internal combustion engines.

With internal combustion engines which are provided with double cams, *i. e.* for 20 "ahead" and "astern" running, it is known to lift the rollers co-acting with the cams off the latter in order to shift the cam shaft unrestrictedly in the axial direction. When performing this manipulation the springs

25 of the spring loaded valves have to be compressed, which performance necessitates a considerable expenditure of energy with multicylinder-motors of a medium size. This lifting requires a great ratio of transmission and therefore involves considerable 30 time for performing the reversal, for this reason it has been proposed to use an auxiliary motor driven by compressed air or pressure oil for carrying out the reversing 35 operation whereby the long periods inherent to a reversal by hand are shortened.

According to the present invention the above mentioned drawback is eliminated in a very simple manner in combining an auxiliary spring with the cam-lifting device 40 which compensates the increasing antagonistic pressure of the springs actuating one or more valves.

One mode of carrying the invention into 45 effect is shown by way of example in the accompanying drawing.

In this drawing W denotes the cam shaft adapted to be displaced in the axial direction, on said shaft two cams V and R for 50 ahead and astern running respectively are provided, which, in a known manner, actuate the spring-loaded valve E by means of

the roller O and the rocking lever H. Previous to displacing the cam-shaft W for reversing purposes, the shaft Y is turned by 55 means of hand wheel D, worm S and lever X whereby the lever Z moves the roller O beyond the range of the path of the revolving cams, whereupon the displacing of the cam shaft W in the axial direction can be 60 performed unrestrictedly. The positions of the parts H, X, B and F after the lifting has been performed are shown diagrammatically in chain dotted lines. The turning moment exerted by the valve spring 65 C on the shaft Y when lifting the roller is compensated in every position of the rocking lever H by an auxiliary spring F acting upon the lever B, as the varying pressure of the valve spring E is compensated by the 70 varying leverage A—A¹ of the direction in which the auxiliary spring acts.

Obviously the number of levers Z provided on the cam shaft may vary according to the 75 number of valves.

I claim:

1. A reversing gear for internal combustion engines, comprising a cam shaft adapted to be axially displaced and provided with ahead and astern cams, a roller co-acting with either of said cams, a rocking lever for transmitting the cam action to a spring-loaded valve, lifting means operatively connected to said roller, and an auxiliary spring combined with said lifting means 80 to compensate the antagonistic action of the valve spring.

2. A reversing gear for internal combustion engines, comprising a cam shaft adapted to be axially displaced and provided 90 with ahead and astern cams, a roller co-acting with either of said cams, a rocking lever for transmitting the cam action to a spring-loaded valve, means operatively connected to said roller to move the latter out of 95 the range of the path of the rotating cams, and an auxiliary spring connected to a lever forming part of said means whereby the leverage of the action of said auxiliary spring alters so that the antagonistic action 100 of the valve spring is always compensated.

In testimony that I claim the foregoing as my invention, I have signed my name.

HANS WIEDERKEHR.
